Primary Examiner — Katherine Glennon

(57) **CLAIM**

The ornamental design for a watch casing with dial, as shown and described.

DESCRIPTION

1. Watch casing with dial
2. Watch casing with dial
  - 1.1 : Front
  - 1.2 : Bottom
  - 1.3 : Top
  - 1.4 : Right
  - 1.5 : Left
  - 1.6 : Back
  - 1.7 : Perspective
- 2.1 : Front
- 2.2 : Back
- 2.3 : Top
- 2.4 : Right
- 2.5 : Left
- 2.6 : Back
- 2.7 : Perspective
- 2.8 : Perspective

1 Claim, 15 Drawing Sheets
